BEVERAGE TANK

Ralph L. Archbold, Euclid, Ohio, assignor to White Consolidated Industries, Inc., a corporation of Delaware
Filed Nov. 20, 1962, Ser. No. 238,972
8 Claims. (Cl. 222—158)

This invention relates to containers and more particularly to a container adapted for storing and transportation of beverage syrup and maintaining the container contents under pressure.

Current designs of soft drink vending machines and soda fountain equipment include the use of a beverage syrup container of about five gallons capacity which is suited for quick connection and disconnection at the vending machine or point of use and for convenient transportation to a central distribution plant. The container is washed, sterilized and refilled with beverage syrup at the distribution plant and thereafter returned to the vending machine or point of use.

It is desirable that such containers be constructed so as to be quickly and easily disassembled for cleaning and where such disassembling and reassembling operations may be performed so as to provide for safety in use when subjected to pressurization. Such container should be inert with respect to chemical reaction with the syrup and cleaning detergents. Stainless steel is often used to form such containers.

It is among the objects of my invention to provide a beverage syrup container or tank which will provide for convenient assembly and disassembly for cleaning and filling and wherein the container is made of resin-bonded fiber glass so as to be resistant to corrosion or chemical reactions and wherein a tank is provided having desirable insulating characteristics and the tank structural parts are utilized in providing a pressure seal contributing to safety in use.

It is a further object of my invention to provide a beverage tank or container according to the preceding object wherein the container is characterized by a cylindrical side wall construction and where the top and bottom sections of the container include peripheral cylindrical portions which are bonded within the cylindrical construction and wherein portions of the side walls extend beyond the top section of the container to provide anchorage for an abutment extending transversely of the container.

It is a further object of my invention to provide a tank according to the preceding objects wherein said transverse abutment includes a lid holding latch and is constructed and arranged to be quickly and easily removed from the container.

It is a further object of my invention to provide a beverage tank having cylindrical side walls with integral ear portions thereof extending above a tank top section having a central opening and wherein the ears are provided with opposed apertures adapted to receive oppositely extending trunnions carried by a lid abutment unit and wherein the lid abutment unit provides a latch which may be rocked or turned to move a lid member toward the opening in the tank top section and wherein fluid pressure within the container is effective to cause a deflection in the tank top section and thus assist in maintaining a pressure seal with the lid.

Other objects and advantages relating to safety and efficiency in operation, economy in manufacture and to ruggedness and long useful life in service will appear from the following description and the appended drawings wherein:

FIG. 1 is a perspective view of a beverage tank made according to my invention;

FIG. 2 is an enlarged plan view of the beverage tank;

2

FIG. 3 is an elevation of the upper portion of the beverage tank with parts in section illustrating disassembly of the lid holding mechanism made according to my invention;

5 FIG. 4 is a sectional view of the lid holding mechanism taken along the plane indicated at 4—4 of FIG. 2;

FIG. 5 is a section along 5—5 of FIG. 2 showing manual manipulation of the lid holding mechanism; and

10 FIG. 6 is an enlarged sectional view of the beverage tank.

The beverage tank of the present invention includes a cylindrical side wall unit indicated in its entirety as at 6. The cylindrical side wall section 6 is made of cured resin-bonded fiber glass. The cylindrical unit 6 is preferably made according to the method and apparatus disclosed in the patent to Wiltshire, No. 3,012,922 wherein a tubular mandrel is rotated while chopped glass fibers and resin are being deposited within the rotating mandrel and the cylindrical section thus centrifugally formed is then cured within the mandrel.

15 The beverage tank of my invention includes a bottom section 7 and a top section 8, which sections are preferably made of resin-bonded fiber glass within matched metal molds. As will be understood by those skilled

20 in the art of fiber glass forming, a metal mold having a cavity conforming to the contour of the exterior of the bottom section is fitted with a pre-form or loose mat of glass fibers and provided with a quantity of resin. Thereafter a matching metal male mold section having

25 an exterior conforming to the interior shape of the end section 7 is pressed within the forming cavity and the fiber glass and resin cured under heat and pressure within such cavity. The top section 8 is similarly formed in matched metal molds. The cured sections 7 and 8

30 include peripheral cylindrical portions 7a and 8a which may be telescoped within the cylindrical side wall section 6. In the case of the top section 8, the center portion is punched out or otherwise removed so as to provide a central opening as at 9 which is adapted to receive 35 a lid 11.

The lower end of the cylindrical section 6 is undercut from the open end thereof to provide a shoulder as at 12. The undercut cylindrical portion as at 13 is accurately machined so as to provide for a snug pressed fit with 40 the peripheral cylindrical portion 7a of the bottom section 7. The proportions are such that the bottom section 7 is telescoped within the cylindrical section 6 so that the tank is supported on a surface by the lower edge of the section 6.

45 The end cap or bottom section 7 is provided with an annular groove 7b in the section 7a. The interior wall of the section 6 is preferably grooved or corrugated in the area opposite the annular groove 7b. The annular opening as formed between the cylindrical section 6 in 50 the area indicated at 7b is then filled with resin binder material to form a secure bond between the cylindrical portion of the container and the end section 7. In this connection the joint is formed and the sections bonded to each other as disclosed in my co-pending application of

55 Balcom and Archbold for "Fiber Glass Tank," filed November 5, 1958, Serial No. 772,026 now Patent No. 3,095,-

60 993, issued July 2, 1963.

The top section 8 of the beverage tank is secured to the cylindrical section 6 as described above and as described in said co-pending application, Serial No. 772,026.

The cylindrical section 6 of the beverage tank is formed to have an overall length to include the ears 15 and 16. The wall sections between the ears 15 and 16 are cut away or punched out from the overall length of the tube and the parts thus cut out are then utilized to provide supplementary ear sections 17 and 18. The supplementary ear portions 17 and 18 are resin-bonded to the integrally

formed ears 15 and 16 as best shown in FIG. 6 wherein surplus resin, as indicated at 19 and 20, forms a smooth fillet at the juncture between the ears and the top section 8.

An opening is provided in the oppositely disposed ear sections and a metal grommet as at 21 and 22 is crimped into place. The metal grommets 21 and 22 along with the supplemental ear sections 17 and 18 efficiently transmit loads from the transverse abutment and handle member 25 to the main cylindrical body 6 of the beverage tank.

The beverage tank is provided with an outlet fitting 26 carried in an aperture formed in the sloping wall of the top section 8. The fitting 26 includes a body 27 which overhangs the fitting aperture and carries a dip tube 28. The body 27 of the outlet fitting is threaded at the exterior thereof and is clamped into place by nut 29. The fitting 26 and the dip tube 28 are utilized to discharge beverage syrup from the beverage tank and it will be understood that the nipple portion 30 of the outlet fitting is adapted to be connected to the hose or tube for conducting the syrup under pressure to its place of use.

It will also be understood that the outlet fitting 26 may be connected to a line valve to close the syrup outlet when the beverage supply is under pressure during transportation.

A gas inlet fitting 31 is also mounted in the section 8. The gas inlet fitting 31 may be constructed substantially as the fitting 26 and preferably includes a check valve (not shown) to maintain fluid pressure in the beverage container after charging the tank with gas. It will be understood that when in use in a vending machine the fitting 31 may be connected to a supply of CO₂ gas to maintain a pressure of about sixty pounds per square inch on the liquid in the tank.

It will be noted in connection with the fitting 26 and the dip tube 28 carried thereby that the slope of the wall in the top section 8 tilts the dip tube 28 in toward the center of the tank so that the lower end of the dip tube as at 28a is adjacent the lowermost portion of the beverage tank. This provides that substantially all of the syrup in the tank may be withdrawn through the dip tube 28.

In forming the cylindrical section 6 which makes up the main body portion of the beverage tank resins and glass are utilized such that the tank is substantially translucent. Thus the beverage tank may have indicia at the exterior thereof as indicated by numerals 1 to 4 which will give a visual indication to the user of the quantity of syrup within the beverage tank.

The locking or clamping mechanism for holding the lid 11 securely in place and provide a carrying handle is indicated in its entirety as at 25. The unit 25 is preferably formed of aluminum and has oppositely extending trunnion portions 40 and 41. The trunnion portions are contoured in cross section as indicated in FIG. 5 so as to provide opposite flat sides 41a and 41b joined to each other by rounded portions 41c and 41d. With the member 25 in the position shown in FIGS. 1, 2, 4 and 6, the rounded portions of the trunnions 40 and 41 bear against the top areas of their grommets 21 and 22, respectively. The lower mid-portion of the member 25 is provided with a cam face indicated at 45 in FIG. 4 and said cam surface, along with an abutment surface 46 carried at the under side of operating lever 47, provides a stable abutment pressing against the upper side of the lid 11.

Preferably the lid 11 is provided with a gasket 11a and a flange 11b surrounding the outlet or opening 9 formed in section 8. The positioning of the member 25 as illustrated in FIG. 4 applies a light sealing pressure to the gasket 11a interposed between the lid and the section 8. Preferably the opening 9 in the top section 8 is proportioned with respect to the area surrounding the opening 9 so that the total area around the opening 9 greatly exceeds the area of the opening. For example assuming that the area of the opening 9 is about eleven square inches for a given tank, the annular area of the cap section 8 around

the opening will have an area of about forty-two square inches.

The flexibility of the fiber glass material forming the section 8 is utilized to assist in sealing at the gasket 11a. Accordingly, a fluid pressure increase in the container caused by the introduction of CO₂ gas through the gas inlet 31 at sixty pounds per square inch will deflect or bend the cap section 8 outwardly against the lid 11. Since the lid 11 is backed up or restrained against movement by the abutment unit 25, the deflection of the section 8 increases the sealing pressure at the gasket 11a.

The member 25 includes spaced integrally formed arcuate ears 49 and 50. The ears 49 and 50 extend downwardly beneath the horizontal area occupied by the lid 11. As shown in FIG. 6, the depending ear 49 is located alongside the flange 11b of the lid and the ear 50 is located alongside the opposite side of the flange 11b. As thus arranged with the cam surface 45 in its lowermost abutting position against the lid 11 and the portion 46 also against the lid 11, as shown in FIG. 4, the member 25 is restrained against horizontal sliding movement sufficient to free either of the trunnion portions from the grommets 21 and 22. When, however, the handle member 47 is grasped as illustrated in FIG. 5 and turned upwardly to the phantom line position of FIG. 5, the ears 49 and 50 are swung into a horizontal area above the lid 11. This "released position" is illustrated in FIG. 3. With the manual handle 47 in its raised position, the assembly 25 may be moved laterally of the container so as to free the trunnion 40 with respect to its grommet 21.

It will also be observed that moving the handle 47 to its "released" or "unlocked" position brings the flattened areas such as 41b of the trunnions into engagement with the upper interior surfaces of the grommets 21 and 22. The positioning of the flattened surfaces provides sufficient clearance of one trunnion in its grommet so that the assembly 25 may be tilted upwardly away from the lid 11 as illustrated in FIG. 3.

It is among the advantages of the interlocking arrangement of lid 11 and the unit 25 that swinging the handle 47 from the position shown in FIG. 4 to the position shown in FIG. 5, releases the pressure on the lid 11 and yet retains the lid 11 in its location underneath the rugged assembly 25. Thus the user as a necessary first step towards disassembly of the lid and container for washing and sterilization must release the gas pressure stored in the container and, at the same time, trap or hold the lid in a position where it cannot fly violently upward and injure the person using the container. It will be observed that it is necessary to slide the unit 25 laterally as illustrated in FIG. 3 before the lid may be removed entirely from the container. Since the depending ears 49-50 prevent lateral sliding movement with the assembly in its locked position, there is no danger of inadvertently releasing the fluid pressure or removing the carrying handle formed by the opening 55 in the assembly 25.

The position of the parts as illustrated in FIGS. 1, 2 and 6 is an "over center" position of the unit 25 and the container may be conveniently carried by the handle portion H of the assembly 25.

The beverage tank assembly made according to my invention thus consists basically of three separately removable parts, namely, the body of the container having side walls and top and bottom sections, the lid 11 for the top opening and the latch-abutment unit 25. All of such parts are significantly free of threads, crevices, or the like, which would tend to collect syrup and be difficult to clean or maintain in a sanitary condition. The arrangement permits large dimensional manufacturing tolerances. The lid and container body are joined to each other through the medium of a flat gasket which is easy to clean and which will accommodate wide dimensional variations. No tools are required for assembly or disassembly.

The completed container may be provided with a re-

silient band 56 at the bottom thereof and a resilient bumper band 57 adjacent the top of the tank.

Although I have described and shown one form of my invention in considerable detail, it will be understood by those skilled in the art that numerous variations may be made therein without departing from the scope of the invention as defined in the following claims.

What is claimed is:

1. A container for liquid comprising a cylindrical main section having side walls of cured resin-bonded fiber glass, a rounded bottom section of cured resin-bonded fiber glass, said bottom section having a cylindrical peripheral portion telescopically arranged within the lower end of said cylindrical main section, a top section of cured resin-bonded fiber glass having a central opening, a sloping annular wall around said central opening and cylindrical peripheral portions telescopically arranged within the upper end of said main section, said main section having oppositely disposed integrally formed ears projecting upwardly above said top section, each of said ears having an aperture, a transverse abutment member having trunnions at each end thereof, the overall length of said transverse abutment member exceeding the distance between said ears, said trunnions being proportioned to fit within said ear apertures, a lid for said central opening in said top section, means to provide sealing engagement between said lid and said central opening, said abutment member having a cam face at the underside thereof adjacent said lid, said abutment member having a manually operable lever extending laterally from said cam for rocking said abutment member about its trunnion mounting in said ear apertures from a first position with said cam face biasing said lid into sealing engagement with said central opening to a second position with the cam face moved away from said lid, said abutment member having spaced integrally formed lugs thereon to embrace opposite sides of the lid and thereby prevent axial movement of the abutment member in its trunnion mounting the abutment member in said first position.

2. A container for holding liquid under pressure comprising a cylindrical main section providing side walls of cured resin-bonded fiber glass, a rounded bottom section of cured resin-bonded fiber glass having a cylindrical peripheral portion telescopically arranged within the lower end of said cylindrical main section, the lower edges of said main section extending below said rounded bottom, a top section of cured resin-bonded fiber glass having a central opening, said top section having an annular wall around said central opening and integrally formed cylindrical portions at the periphery of the annular wall telescopically arranged within the upper end of said main section, said telescoped cylindrical portions of said top, bottom and main sections being bonded to each other, said main section having diametrically spaced integrally formed ears projecting upwardly above said top section, said ears having diametrically aligned apertures, a transverse abutment member having trunnions at each end thereof mounted in said ear apertures, the overall length of said transverse abutment member including the trunnions exceeding the distance between said ear apertures, said trunnions being proportioned to fit within said ear apertures for rocking and axial sliding movement, a lid for said central opening in said top section, means to provide sealing engagement between said lid and said central opening said abutment member having a cam face centrally located at the underside thereof adjacent said lid, said abutment member having a manually operable rock lever extending laterally from said cam face for rocking said abutment member about its trunnion mounting in said ear apertures from a locked position with said cam face biasing said lid into sealing engagement with said central opening and to a released position with the cam face moved away from said lid, and means to prevent sliding

movement of the abutment member in said ear apertures in said locked position.

3. A beverage dispensing container comprising a cylindrical main section having side walls of cured resin-bonded fiber glass, a rounded bottom section of cured resin-bonded fiber glass, said bottom section having a cylindrical peripheral portion telescopically arranged within the lower end of said cylindrical main section, a top section of cured resin-bonded fiber glass having a central opening, a sloping annular wall around said central opening and cylindrical peripheral portions telescopically arranged within the upper end of said main section, a discharge opening in said sloping wall, said main section having oppositely disposed integrally formed ears projecting upwardly above said top section, each of said ears being formed by a continuation of the wall of said main section and having an aperture, a transverse abutment member having trunnions at each end thereof, the overall length of said transverse abutment member exceeding the distance between said ear apertures, said trunnions being mounted within said ear apertures for rocking and sliding movement, a lid for said central opening in said top section, means to provide sealing engagement between said lid and said central opening, a dip tube secured to said top section at said discharge opening within the container, said dip tube terminating adjacent the center of said rounded bottom section, said abutment member having a cam formed at the underside thereof adjacent said lid, said abutment member having a manually operable lever extending laterally from said cam for rocking said abutment member about its trunnion mounting in said ear apertures from a locked position with said cam biasing said lid into sealing engagement with said central opening and to a released position with the cam face moved away from said lid, said abutment member having lugs thereon to engage the lid and thereby prevent axial sliding movement of the abutment member in said locked position.

4. A beverage tank comprising an upright elongated cylindrical main section having side walls and top and bottom sections of cured resin-bonded fiber glass, said top section having a central opening and an annular portion around said central opening, a lid for said central opening, said annular portion having a projected area more than three times the area of the central opening, said tank having oppositely arranged ears projecting upwardly above said top section, each of said ears having a trunnion receiving aperture, a transverse abutment member having trunnions at each end thereof, said transverse abutment member having an overall length exceeding the distance between the ear apertures, said transverse abutment member having a cam face at the underside thereof adjacent the said lid, a sealing gasket carried by the lid and arranged to be interposed between the edge of the central opening in the top section and the underside of the lid, said abutment member having a manually operable lever for turning the abutment member in its trunnion mounting in said ears, means including said trunnions and said cam face effective to establish a fixed position of said lid relative to the tank as the abutment member is turned through about 90° from a released position to a sealed position, and means to introduce fluid pressure within the beverage tank to deflect the annular portion around the opening upwardly to supplement the sealing pressure at said gasket when the abutment member is in its said locked position.

5. A beverage tank having cylindrical side walls and top and bottom sections formed of cured resin-bonded fiber glass, the side walls of said tank having oppositely disposed upwardly projecting ears proportioned to extend above the top section of the tank, supplemental sections of cured resin-bonded fiber glass having the same arcuate shape as said ears mounted within said oppositely disposed ears and bonded thereto, said ears and supplemental sections being bonded to each other and having aligned trunnion apertures, said ears and supplemental

sections having a metal trunnion grommet mounted in the apertures, said top section of the beverage tank having a central opening, a lid for said opening, means to provide sealing engagement between said lid and said central opening, clamping means for said lid comprising an elongated metal abutment member, said abutment member having trunnions at each end thereof proportioned to fit within said grommets, said trunnion members each having an axial extent whereby the abutment member may be slid laterally of the tank within the grommets so as to free one trunnion from its grommet and permit upward swinging movement of the abutment member, said abutment member having an integrally formed lid cam surface at its underside, said abutment member having a laterally extending operating handle whereby the abutment member may be rocked in its trunnion mounting from a sealed position exerting pressure on said lid and to a released position separating the cam surface from said lid, said abutment member having spaced dependent lugs adapted to embrace opposite peripheral portions of said lid when the trunnion member is in its sealed position and thereby preventing lateral sliding movement of the abutment member in its sealed position.

6. A beverage dispensing tank having side walls and top and bottom sections formed of translucent cured resin-bonded fiber glass, the side walls of said tank having vertically spaced indicia showing liquid measure, said side walls having oppositely disposed upwardly projecting integrally formed ears proportioned to extend above the top section of the tank, supplemental ear sections of cured resin-bonded fiber glass mounted within said oppositely disposed integrally formed ears and bonded thereto, each of said integrally formed and supplemental ears having aligned apertures, each of said ears having a tubular metal grommet mounted in the apertures, said top section of the beverage tank having a central opening, a lid for said opening, means to provide sealing engagement between said lid and said central opening, clamping means for said lid comprising an elongated metal abutment member, said abutment member having trunnions at each end thereof proportioned to fit within an ear grommet, said trunnion members having an axial extent greater than the axial extent of the grommet whereby the abutment member may be slid laterally of the tank and axially on the trunnions within the grommets so as to free one trunnion from its grommet and permit upward bodily swinging movement of the abutment member about the other grommet, said abutment member having an integrally formed lid engaging surface at its underside, said abutment member having a laterally extending operating handle whereby the abutment member may be rocked in its trunnion mounting from a sealed position exerting pressure on said lid to a released position releasing the lid engaging surface with respect to said lid, said abutment member having means to engage portions of said lid when the trunnion member is in its sealed position and thereby preventing lateral sliding movement of the abutment member in its sealed position.

7. A beverage dispensing tank having side walls and top and bottom sections formed of translucent cured resin-bonded fiber glass, the side walls of said tank having fluid measure indicia thereon, said tank having oppositely disposed upwardly projecting ears extending above the top section of the tank, reinforcing ear sections of cured resin-bonded fiber glass secured to said upwardly projecting ears, said ears having aligned apertures, a metal grommet mounted in the apertures, said top section of the beverage tank having a central opening and an annular

area around the central opening, a lid for said opening, means for providing sealing engagement between said lid and said central opening, a gas inlet passage and a dispensing passage mounted in said annular area of the top section between said ears, a dip tube secured to said top section in communication with said dispensing passage, said dip tube extending adjacent to bottom section of said tank, clamping means for said lid comprising an elongated abutment member, said abutment member having trunnions at each end thereof proportioned to fit within said oppositely disposed grommets, said trunnions having a cross section to provide areas of different radii, said trunnion members each having an axial extent whereby the abutment member may be slid laterally of the tank within the grommets so as to free one trunnion from its grommet and permit upward swinging movement of about the other trunnion within its grommet, said abutment member having a lid engaging surface at its underside, said abutment member having a laterally extending operating handle whereby the abutment member may be rocked in its trunnion mounting from a sealed position exerting pressure on said lid to a released position releasing the lid engaging surface with respect to said lid.

8. A beverage dispensing tank comprising an upright elongated cylindrical translucent main section having side walls and top and bottom sections of cured resin-bonded fiber glass, quantity indicia on said side walls, said top section having a central opening and a sloping annular portion around said central opening, a lid for said opening, said annular portion having an area more than three times the area of the central opening, a gas inlet means in said annular area for introducing gas at about sixty pounds per square inch to said tank, said tank having oppositely arranged ears projecting upwardly above said top section, a beverage dispensing outlet in said annular area, a dip tube secured to said top section within said tank and communication with said beverage dispensing outlet, said dip tube extending adjacent said bottom section of the tank, each of said ears having a trunnion receiving aperture, a transverse abutment member having trunnions at each end thereof, said transverse abutment member having an overall length exceeding the distance between the ear apertures, said transverse abutment member having a lid engaging surface at the underside thereof adjacent the said lid, a sealing gasket carried by the lid and arranged to be interposed between the edge of the opening in the top section and the underside of the lid, said abutment member having a manually operable means for moving the abutment member in its trunnion mounting in said ears and thereby move the lid engaging surface to a sealed position resisting deflection of the top section resulting from the introduction of said gas to the container.
